DESIGN FOR A LIFTING TONG

Louis Martinelli, San Francisco, Calif.

Application November 1, 1944, Serial No. 116,091

Term of patent 14 years

(Cl. D44—4)

To all whom it may concern:

Be it known that I, Louis Martinelli, a citizen of the United States of America, resident of San Francisco, in the county of San Francisco and State of California, have invented a new, original, and ornamental Design for a Lifting Tong, of which the following is a specification, reference being had to the accompanying drawing, forming a part thereof.

Fig. 1 is a top plan of a lifting tong showing my new design; and,

Fig. 2 is a front elevation of the same.

I claim:

The ornamental design for a lifting tong, substantially as shown.

LOUIS MARTINELLI.
